UNITED STATES PATENT OFFICE.

WALTER LAWRENCE McNULTY, OF PEACE DALE, RHODE ISLAND.

MINE.

1,327,488.

Specification of Letters Patent.

Patented Jan. 6, 1920.

Application filed August 8, 1919. Serial No. 316,121.

To all whom it may concern:

Be it known that I, WALTER L. McNULTY, a citizen of the United States, residing at Peace Dale, in the county of Washington 5 and State of Rhode Island, have invented new and useful Improvements in Mines, of which the following is a specification.

The present invention comprehends the provision of a float mine equipped with a 10 wireless receiving apparatus, so that the mine can be exploded from a remote point.

The nature and advantages of the invention will be better understood from the following detailed description taken in connection with the accompanying drawing, the invention residing in the construction, combination and arrangement of parts as claimed.

In the drawing forming part of this specification like numerals of reference indicate 20 similar parts in the several views wherein:—

Figure 1 is a sectional view through both the float and the explosive member suspended therefrom.

Fig. 2 is an end elevation partly in section of the float member.

Referring to the drawing in detail, A indicates generally the float while the form of explosive member is indicated generally 30 at B. The float may be of any suitable construction but preferably consists of a casing 10 divided by the partitions 11 to define air chambers 12. The casing 10 is further divided by the partitions 13 to provide 35 a compartment 14 for the reception of the storage batteries while the compartment 15 accommodates the wireless receiving apparatus. The receiving apparatus may be of any desired construction, the antenna or 40 aerial wire thereof being supported between the two standards 16 rising from the float and braced by means of guy wires 17. One side of the casing 10 may be detachably or 45 removably associated with the remaining portion of the casing to permit access to be had to the receiving apparatus when desired.

The mine or explosive member indicated at B is suspended by the cables 18 to the 50 float casing 10 and may be of any suitable construction. Within the member B is a casing 20 at the lower end of which is arranged the detonator while a plunger or

firing pin is indicated at 21. Arranged at the opposite sides of the plunger 21 and 55 normally engaging the latter to hold the same elevated or spaced from the detonator 22, are pivoted hook like elements 23. Carried by the casing 20 in juxtaposition to the hook like elements 23 are the magnets 24 60 which are connected in circuit with the receiving apparatus of the float by means of the wires 25. In practice, the waves emitted from the sending apparatus fall upon the antenna or aerial wire 15' of the wireless 65 receiving apparatus whereby current is directed to the magnets 24. When the latter are energized, the upright elements 23 are attracted and moved out of engagement with the plunger 21. The spring 26 then functions to forcibly drive the plunger against 70 the detonator 22 with a resultant explosion of the member B. Manifestly, the mine or explosive member B can be controlled from 75 remote points in simple yet positive manner.

While I have shown and described what I consider the preferred embodiment of the invention, I desire to have it understood that I do not limit myself in this connection and that such changes may be resorted to when 80 desired as fall within the scope of what is claimed.

What I claim is:—

1. The combination with a float, of an explosive member suspended from said float 85 and including a detonator, a spring pressed plunger, pivoted hook-like elements normally holding the plunger in spaced relation to the detonator, and electrical means connected in circuit with said receiving apparatus for effecting a release of said elements to permit actuation of said plunger.

2. The combination with a float, of an explosive member suspended from said float 95 and including a spring pressed plunger, pivoted hook-like members arranged at opposite sides of said plunger and designed to engage the latter to hold the same in an inactive position, a detonator, a magnet arranged in juxtaposition to said pivoted members and connected in circuit with said receiving apparatus, so as to attract said pivoted members when the magnets are energized and thereby effect the release of said plunger for the purpose specified.

3. A float mine comprising a float casing,

partitions dividing said casing into air chambers at the opposite ends of the casing, a third partition dividing the space between the aforementioned partitions into separate compartments for the reception of a wireless receiving apparatus and batteries, said receiving apparatus including an antenna pro-

jecting above the float, and a mine or explosive suspended from said float and including an electrically operating detonating mechanism. 10

In testimony whereof I affix my signature.

WALTER LAWRENCE McNULTY.
